WALL CABINET

Filed Nov. 19, 1928

INVENTOR
LELAND S. ROSENER
BY Charles S. Evans
HIS ATTORNEY.

UNITED STATES PATENT OFFICE

LELAND S. ROSENER, OF SAN FRANCISCO, CALIFORNIA

WALL CABINET

Application filed November 19, 1928. Serial No. 320,408.

My invention relates to cabinets for mounting between the studs of a building, such as bathroom or medicine cabinets or the like.

An object of my invention is to provide 5 a cabinet having a mirror closure which may be opened without displacing the position of the mirrored image.

Another object of my invention is to provide a cabinet which may be opened without 10 disturbing objects placed in front thereof.

My invention possesses other objects and 15 valuable features, some of which will be set forth in the following description of my invention which is illustrated in the drawings forming part of the specification. It is to be understood that I do not limit myself to the showing made by the said description and drawings, as I may adopt varying forms 20 of my invention within the scope of the claims.

Referring to the drawings:

Figure 1 is a front elevation of the cabinet of my invention as mounted in the wall of a building.

25 Figure 2 is a vertical sectional view of the cabinet and the adjacent wall structure, the plane of section being indicated by the line 2-2 of Fig. 1.

Figure 3 is a fragmentary horizontal sectional view, taken on the line 3-3 of Fig. 1, and showing the arrangement of the cabinet, mirror and balancing weights with respect to the wall structure.

A preferred embodiment of my invention 35 comprises a wall cabinet having a top 6 and bottom 7, sides 8 and back 9. This is set in an opening in the wall between the studs 11, and is spaced from the studs by blocks or pulley stiles 12. The rough opening is preferably made about half again as high as the 40 cabinet and is surrounded by a light frame 13 secured to the studding and against which the lath and plaster or other wall surface 14 is carried. The bottom of the cabinet rests 45 upon a horizontal tie-beam 16 set flatwise between the studs. Another parallel tie-beam 17 is set edgewise across the back of the opening above the cabinet, and blocks 18 between this tie-beam and the cabinet top serve 50 to hold the cabinet rigidly in place. A light

bar 19 preferably passes across the front of the cabinet top between the pulley stiles.

The cabinet closure comprises a mirror 21, held in a light channel metal frame 22 which has a lug or ear 23 secured to each side, 55 spaced preferably about half way down from the top of the mirror. A cord 24 is fastened to each lug, and passes upward, parallel to the plane of the mirror and over a pulley 26, which is mounted in the pulley stile adjacent 60 the top of the rough opening, or about half the height of the mirror above the cabinet. The cords 24 terminate in counterweights 27 for balancing the weight of the mirror.

Secured to the studding thru the frame 13 65 is a finishing frame 28 which conceals the side and upper edges of the mirror and also its balancing system. In the upper part of the frame 28 is mounted a panel 29, which may be of wood, or, if desired, a fixed mirror. 70 A lift 31 is preferably fixed to the bottom of the frame 22 for manipulating the closure.

The ordinary medicine or wall cabinet carries a shaving mirror mounted on a hinged door. Shaving paraphernalia is kept 75 within the cabinet, and is placed on the edge of the wash basin when in use. If the door be opened during the shaving process the shaver loses sight of himself in the mirror, and frequently knocks some of his equipment to the floor in the process. It will be seen that with my closure the cabinet may be 80 opened without disturbing anything which may be in front of it, and furthermore that the reflected image does not move with the 85 mirror, so that additional accessories may be secured without interrupting the shaving process.

Altho I have shown the cord lugs placed 90 centrally of the mirror sides, it is obvious that they may be placed nearer the bottom and the size of the rough opening reduced if guides be provided in which the frame 22 may slide or the bottom of the frame be 95 weighted. Usually, however, the form here shown will prove most convenient and economical.

I claim:

1. A cabinet adapted for placement between the studs of a building, comprising 100

sides, a block spacing each side from the adjacent stud, a mirror slidably disposed adjacent the front edges of the sides, means for balancing the weight of the mirror arranged in the space between side and stud, and a frame mounted on the studs and concealing the edges of the mirror.

2. A cabinet adapted for placement between the studs of a building, comprising sides, a block spacing each side from the adjacent stud, a mirror slidably disposed adjacent the front edges of the sides, a pulley in each spacing block, a cord attached to each side of the mirror and passing over the adjacent pulley, a counterweight on each cord, and a frame mounted on the studs and concealing the edges of the mirror.

3. A cabinet adapted for placement between the studs of a building, comprising sides, a frame mounted independently of the cabinet and removably secured to the studs, a mirror slidably disposed between the frame and the front edges of the sides, and means for balancing the weight of the mirror arranged outside the cabinet and concealed by the frame.

4. A cabinet adapted for placement between the studs of a building, comprising sides, a block spacing each side from the adjacent stud, a mirror slidably disposed adjacent the front edges of the sides, means for balancing the weight of the mirror arranged outside the cabinet and supported by the spacing blocks, a frame mounted independently of the cabinet and removably secured to the studs, and a panel positioned above the cabinet and mounted on the frame for concealing the balancing means.

In testimony whereof, I have hereunto set my hand.

LELAND S. ROSENER.
